UNITED STATES PATENT OFFICE.

WILHELM JEHLE, OF DONAUESCHINGEN-KARLSHOF, GERMANY, ASSIGNOR OF THIRTY-THREE AND ONE-THIRD PER CENT TO EMANUEL HERTZ, OF NEW YORK, N. Y., AND THIRTY-THREE AND ONE-THIRD PER CENT TO CARL HIRSCH, OF KREUZLINGEN, SWITZERLAND.

MUFFLER FOR INTERNAL-COMBUSTION ENGINES.

Application filed December 6, 1926, Serial No. 152,957, and in Germany July 5, 1926.

My invention relates to mufflers for internal combustion engines, particularly for motor-car engines, and it is an object of my invention to provide a muffler of the kind described in which the exhaust gases are cooled and expanded rapidly.

My muffler is of the general type in which two sets of spiral passages are separated by a transverse partition. In order to effect the rapid cooling and expansion aforesaid, I provide slots in the partition through which a certain percentage of the comparatively hot exhaust gases which have just entered the muffler, is allowed to mix with the comparatively cool gases in the more remote parts of the muffler. The fresh gases, being under high pressure, flow at comparatively high speed and in mixing with the cooler low pressure gases, give up to them a portion of their mechanical and thermic energy so that the cooler gases are accelerated by the hotter gases while, on the other hand, the hotter gases are cooled by contact with the cooler ones. In this manner, back pressure of the gases in the muffler is efficiently eliminated and the cooling action of the ambient air is supplemented by the mixing of the hotter and cooler gas particles as described.

It is another object of my invention to provide a muffler of the kind described which is simple in construction and therefore suitable for quantity production.

In the drawings affixed to this specification and forming part thereof a muffler embodying my invention is illustrated diagrammatically by way of example.

In the drawings

Fig. 1 is an elevation, partly in vertical section, of the muffler,

Fig. 2 is a plan view of the lower half of the muffler casing showing the transverse partition partly broken away.

Referring now to the drawings, *a* and *c* are the upper and lower halves of the muffler casing. Each half constitutes a spiral passage and a top or bottom plate with corrugated depressions. *i* is a transverse partition plate which is inserted between the two halves *a* and *c*, and *k* is a screw by which the two halves *a*, *c* are connected, clamping the partition *i* between them. The spiral passages of the upper and lower halves of

the casing are connected by a hole *f* in the partition *i* which surrounds the central screw *k*. Slots *g* are formed in the partition *i* and slots *h* are formed in the walls of the spiral passage of the lower half *c*. The object of these latter slots is similar to that of the slots *g* in the partition *i*, that is, they tap a certain percentage of comparatively hot gas and allow it to mix with the cooler gas. An inlet pipe *b* is connected to the upper half *a* of the casing and *d* is an exhaust pipe at the lower half *c*. *l* are depressions between the reaches of the spiral passages in the casings *a* and *c* by which ambient air is admitted so as to increase the cooling surface of the muffler.

Preferably the slots *g* in the partition *i* and the slots *h* in the walls of the lower half *c* are so arranged that the central line of the slots *h* extends through the centre of the adjacent slots *g* as will appear from Fig. 2.

The muffler operates as follows:

The exhaust gases are admitted to the passage of the upper half *a* through the pipe *b* and flow in this passage as far as the central hole *f* in the partition *i*. On their way through the passage of the upper half, a certain percentage of the comparatively hot gases which are under comparatively high pressure, escapes into the passage of the lower half *c* where the hot and high-pressure jets act on the cooled and expanded gases in the manner of an injector so as to eliminate back pressure. At the same time, the hot high-pressure jets from the slots *g* are cooled and expanded in contact with the cooled and expanded flow of gases in the lower half *c* so that they lose part of their mechanical and thermal energy. A similar action is achieved by the slots *h* in the partitions between the reaches of the passage in the lower half *c*. As the gases issuing from these slots are hotter and under higher pressure than those in the adjacent reach of the passage they will accelerate the gases and give up a portion of their heat to them, as described. Due to the particular arrangement of the slots *g* with respect to the slots *h* the jets from the slots *h* impinge on the jets from the slots *g* in the partition *i*, exerting an intense cooling action on the comparatively hot jets from *g*.

The slots *g* in the partition *i* allow the

gases to expand rapidly immediately upon their entering the muffler and at the same time they are intensely cooled. Back pressure in the muffler is eliminated by the acceleration which the hotter and more rapidly flowing gases impart to the cooler and more slowly flowing ones so that the gases are discharged rapidly and uniformly. Besides, a high percentage of the heavier constituents of the gases, oil vapours and the like, are condensed by the rapid cooling and the mechanical action of the slots so that smoke emission is reduced.

Another advantage of the muffler according to my invention is the readiness with which it may be divided for inspection and cleaning, all that is required being unscrewing of the screw *k*. The pipes *b* and *d* may be arranged at any desired angle and a hole 20 *m* is provided in one of the parts, for instance the lower half *c* which is engaged by a pin *m* so that the two halves when connected will be in a given relative position.

I wish it to be understood that I do not desire to be limited to the exact details of construction shown and described for obvious modifications will occur to a person skilled in the art.

I claim:—

30 1. An engine muffler comprising a casing having depressions in opposite walls thereof, and a partition having a substantially central opening within said casing and dividing the same into separate sections, said sections 35 having spiral passages communicating with each other through said central opening.

2. An engine muffler comprising a casing having depressions in opposite walls thereof, and a partition having a substantially central opening within said casing and dividing the same into separate sections, said sections having spiral passages communicating with each other through said central opening, said partition having slots permitting communication between sections at points other than the central opening.

3. An engine muffler comprising a casing having depressions in opposite walls thereof, and a partition having a substantially central opening within said casing and dividing the same into separate sections, said sections having spiral passages communicating with each other through said central opening, the walls of one of said passages and said partition having slots permitting communication between sections at points other than the central opening.

4. An engine muffler comprising a casing having depressions in opposite walls thereof, and a partition having a substantially central opening within said casing and dividing the same into separate sections, said sections having spiral passages communicating with each other through said central opening, the outer end of one of the passages ter-

minating in an inlet and the outer end of the other passage terminating in an outlet, said partition and the walls of said other spiral passage having complementary positioned slots for causing an intermixture of the hot 70 and cold gases passing through the muffler.

5. An engine muffler comprising a casing having inlet and outlet ports, a partition having a substantially central opening within said casing and dividing the same into separate sections, said sections having spiral passages communicating at their inner ends with each other through said central opening, the outer end of one of the passages terminating in the inlet port and the outer end 75 of the other passage terminating in the outlet port, said partition and the walls of said other spiral passage having complementary positioned slots arranged so that the axis of each slot in the walls intersects the axis of 80 the adjacent slot in said partition.

6. An engine muffler comprising a sectional casing, a transverse partition having a central opening in said casing and dividing the same into separate chambers, each of 90 the chambers having a substantially coiled passage communicating at their inner ends with each other through said central opening, said partition and the walls of one of 95 said chambers having complementary positioned slots therein for causing an intermingling of a portion of the hot and cold gases, and means detachably connecting said sections.

7. An engine muffler comprising a sectional casing having depressions in the top and bottom thereof, a transverse partition having a central opening in said casing and dividing the same into separate chambers, each of the chambers having a spiral passage 100 communicating at its inner end with said central opening, the outer end of one of the passages terminating in an inlet port and the outer end of the other passage terminating in an outlet port, means for detachably securing said sections together, and means for 105 causing a mixture of the hot and cold gases at predetermined points within said other spiral passage.

8. An engine muffler comprising a casing having inlet and outlet ports, a transverse partition in said casing dividing the same into separate sections, a spiral passage formed in each of said sections, and communicating at their inner ends with each other, the outer end of one of said passages terminating in the inlet port and the outer end of the other passage terminating in the outlet port, and means within said casing 115 whereby the gases are expanded and cooled 120 as they pass through the spiral passages.

Signed at Stuttgart, Germany, this 21st day of August A. D. 1926.

WILHELM JEHLE.
